ADJUSTABLE MECHANISM FOR TUBE
MILL ROLLS

Nelson D. Abbey, Toledo, Ohio

Application October 28, 1946, Serial No. 706,150

1 Claim. (Cl. 153—54)

1

This invention relates to the manufacture of metal tubing and particularly to a tube mill in which substantially a continuous metal ribbon is shaped into tube form and then seamed.

The invention has for an object the production of a new and improved assembly employing cooperating forming rolls between which the metal strip is guided and shaped into tubular form.

Other objects of this invention are to produce in a tubing mill a forming roll assembly having a pair of cooperating rolls adapted to be adjusted vertically and laterally with respect to each other by new and improved means; to enable vertical adjustment of one roll relative to the other rapidly and accurately to be made in a novel and efficient manner; and to enable minute lateral or axial adjustment of one roll relative to the other rapidly and accurately to be made without the necessity of using troublesome and time consuming spacing devices.

Other objects and advantages of the invention reside in the novel features of the construction, arrangement, and operation as will hereinafter appear, and for purposes of illustration but not of limitation, an embodiment of the invention is shown in the accompanying drawings in which,

Figure 1 is a vertical sectional view of a forming roll assembly;

Figure 2 is a sectional view taken along the line 2—2 of Figure 1;

Figure 3 is a sectional view taken along the line 3—3 of Figure 1;

Figure 4 is a rear end elevation of the roll housing, and

Figure 5 is a fragmentary elevation showing a pair of forming rolls misaligned or out of operative relation to each other.

In the usual tube mill a plurality of cooperating pairs of grooved forming rolls are employed to engage portions of an interposed metal strip. The rolls of each pair are annularly contoured in such manner that upon engagement with the metal strip, it is worked in stages gradually to be transformed from a flat metal strip into a continuous tube. The stepwise formation, as effected by the operation of successive pairs of rolls, enables tubing continuously and rapidly to be produced from an endless metal ribbon. Manifestly such successive high speed operations present many factors affecting not only the quality of the product, but the continuity of the process.

For example, if one roll of a pair of forming rolls is laterally offset from the other, as illus-

trated in Figure 5 of the drawings, the side thrust operating on the interposed rapidly moving metal strip is such as will cause the material to shift in the lateral direction and jump from between the forming rolls, thereby to interrupt the process. Even though the metal strip may not become unthreaded, as when the material is substantially enclosed by the contoured forming rolls in the latter stages of the process, the effect of 10 the offset is improperly to work the strip in a manner to produce an unsuitable tube due to out of roundness, and to produce surface imperfections as a result of the ironing action between the metal strip and the offset rolls. Instances also frequently arise wherein an interchange of rolls is desired, or variation of the operating pressure between the rolls and material is necessitated, and in such instances it is 15 expedient to provide means enabling vertical adjustment of one roll support relative to the other without disturbing their driving relation or alignment.

For such purposes, I provide for each pair of forming rolls a roll housing having a driving shaft and a driven shaft on which the pair of rolls are respectively mounted, the driven shaft being adapted bodily to be adjusted radially or vertically and longitudinally or axially relative to the driving shaft without disturbing their 20 driving relation or alignment. This enables one roll of each pair to be adjusted radially or axially with respect to the other roll.

Since each roll housing is substantially the same, the principal difference between the various sets of rolls residing in the contour of the rolls, a description of one assembly is considered sufficient.

Referring to the drawings, there is illustrated upper and lower cooperating forming rolls 10 and 11 fixed to the end portions of upper and lower shafts 12 and 13 respectively which extend longitudinally through and are journaled in a roll housing H. The roll housing is formed of upright front and rear frame plates 14 and 15 seated in grooves 16 and 17 respectively in a sub base or platform 18. Integral frame arms 19 and 20 extending upwardly in parallel relation from the upper end portions of each frame plate 14 and 15 divide the roll housing into upper and lower sections 21 and 22 respectively, (Figure 3), and mounted in the upper end of each frame arm is a gear housing 23.

The upper shaft 12 is journaled in a floating section 24, and is adapted to be vertically and longitudinally adjusted relative to the upper frame

section 21, but the lower shaft 13 is stationarily journaled in the lower frame section 22. Thus, by means later to be described, the upper shaft is vertically and longitudinally adjusted relative to the lower shaft.

The forming rolls 10 and 11 are each keyed to reduced end portions 25 of their respective shafts and these end portions project outwardly beyond the front frame plate 14. Sleeves or spacers 26 and 27 on each shaft respectively are interposed between a shoulder 28, formed by the reduced end portion, and the adjacent roll, and also between the opposite face of each roll and an end nut 29 which threadably engages a threaded end portion 30 on each shaft. Removal of either roll is made possible by unscrewing the respective end nut 29 and removal of the spacer 27.

Roller bearing units 31 and 32 in the front and rear frame plates 14 and 15 respectively engage spaced portions of the lower shaft 13, thereby to enable free rotational movement.

A lock nut 33 which threadably engages a threaded portion 34 of the shaft 13 abuts the lower race of the bearing unit 32 to operate as a stop preventing rearward shifting movement thereof. The inner race of the bearing unit 31 abuts a shoulder 35 on the shaft 13 and prevents forward shifting movement of the shaft. Interposed between the bearings 31 and 32 are spacers or sleeves 36 and 37. The spacer 37 is disposed between the forward end of the lower race of the bearing unit 32 and a spur gear 38 which is keyed to an intermediate portion of the shaft. The spacer 36 is disposed between the other side of the gear 38 and the rearward end portion of the lower race of the bearing unit 31. Thus, it will be apparent that the lower shaft 13 is held against axial or radial movements but is free to rotate.

Cap members 39 and 40 are suitably secured to the front and rear faces respectively of the front frame plate 14 and substantially enclose the opening 41 in which the roller bearing unit 31 and the shaft 13 are mounted. An annular flange 42 on each cap member firmly engages the peripheral wall defining the opening 41 in the frame plate and abuts opposite side walls of the upper race of the bearing unit 31, thereby to prevent longitudinal shifting movement of the bearing unit 31, and in turn the shaft 13 and associated parts.

Another pair of cap members 43 and 44 are suitably secured to the rear frame plate 15 and substantially cover the opening 45.

An annular flange 46 on each cap member engages the inner periphery of the opening 43 to cooperate in preventing shifting movement, but they do not extend.

Bolted onto the rearward end portion of the cap member 44 is a housing 47 into which the rear end portion of the lower shaft 13 extends. The outer end of the housing 47 is closed by a cover plate 48 removably held thereon by bolts 49. Extending transversely through the lower portion of the housing 47 is a power driven shaft 50 having a worm 51 in engagement with a worm gear 52. The worm gear 52 is keyed to a reduced end portion 53 of the shaft 13. The worm gear 52 abuts a shoulder 54 formed by the reduction in shaft diameter, while the other side is engaged by an end cap 55 secured to the shaft 13 by bolts 56. Normally, the housing 47 is packed with a lubricant, such as grease, which is prevented from leaking into the roll housing by a sealing ring 57.

The floating section 24 mounting the upper shaft 12 comprises a pair of housing plates 60 and

61 rectangular in cross section and of substantial thickness dimensionably adapted slidingly to fit between the forward and rearward frame arms respectively and to be flush with the front end rear edges thereof. Roller bearing units 62 and 63 mounted in central apertures in the housing plates 60 and 61 respectively support the upper roll shaft 12 to enable free rotational movement. Similarly assembled, as described with reference to the lower roll shaft 13, a lock nut 64 secured to the threaded end portion 65 of the shaft, spacers 66 and 67, and a spur gear 68 keyed to an intermediate portion of the shaft 12 between the spacers, are disposed on the shaft. As assembled, 15 the above parts are not moveable longitudinally or vertically relative to each other.

Cap members 69 and 70 are bolted to opposite sides of the plate 60 to conceal the opening in which the bearing unit 62 is mounted. An annular flange 71 in each cap member engages the peripheral edge portions of the plate aperture to prevent relative vertical shifting movement, and is spaced from the side walls respectively of the upper race of the bearing 62 to enable limited 25 longitudinal shifting movement thereof. To enable vertical adjustment but to militate against rearward shifting movement of the entire floating section 24, the lateral edge portions of the front cap member 69 overlaps a portion of the front 30 wall of the frame arms 19 and 20.

A sleeve 72 is interposed between the outer race of the roller bearing unit 63 and the wall of the aperture in the rear plate 61. An inwardly extending flange 73 integral with the forward end 35 of the sleeve 72 engages the forward end wall of the upper race of the bearing unit 63. An annular sleeve 74 extending forwardly from a cover plate fits within the sleeve 72 and bears against the rear end wall of the upper race of the bearing unit 63. The ends of the sleeves 72 and 74 are connected by bolts 75a, thus the upper shaft and the entire sleeve assembly is adapted to move bodily longitudinally of the floating section, the movement being limited by the spacings between the sleeve and shaft parts and the adjacent flanged surfaces of the cap members.

Another cap member 76 is secured to the forward wall of the plate 61 to conceal the opening therein, an annular flange 77a on the cap member 50 76 being spaced from the sleeve 72 to enable the longitudinal adjustment previously mentioned. It may be here pointed out that the required longitudinal shaft adjustment in order to effect the desired relative position between rolls 55 is ordinarily very small, preferably not exceeding $\frac{1}{8}$ of an inch.

Controlled longitudinal or axial adjustment of the shaft 12 relative to its housing is effected by means of a non rotatable set screw 77. The head 60 78 of the set screw fits in a correspondingly shaped socket in the rear wall of the plate 61 and is held in place by means of a cap member 79 suitably secured to the plate 61. The lateral edge portions of the cap member 79 overlap the 65 rear wall of the associated frame arms and assist in guiding the floating section vertically but militate against relative forward shifting movement thereof. The threaded shank 80 of the set screw extends through and threadedly engages 70 an ear 81 integral with and extending upwardly from the sleeve 72. Lock nuts 82 and 83 engage opposite sides of the ear and by loosening one and tightening the other, minute longitudinal shifting movement of the sleeve 72, and correspondingly the entire shaft 12 can be effected. The 75

entire upper shaft assembly in this manner is axially shifted bodily relative to the lower shaft thereby to shift the roll 10 crosswise or axially relative to the roll 11.

Vertical adjustment of the floating section 24 is effected in response to the actuation of a pair of screw-threaded, non-rotatable bolt members 84 and 85, the head end portions 86 of which are held against turning in sockets in the upper surfaces of the plates 60 and 61 respectively. Aper-tured plates 87 secured to the upper surfaces of the plates 60 and 61 respectively embrace the held ends 86 of the bolts to hold them in place. 88 and 89 are a pair of worm gears supported in the housing 23, previously described. Cap members 91 and 92 close the upper open end portions of the gear housing and integral depending sleeves 93 bear against the worm gears.

Each worm gear 88 and 89 is centrally aper-tured and threaded operatively to engage the screw-threaded shank 93 of the bolt members respectively. Thus, upon rotation of the worm gears, in response to turning movement of a common worm 94, which extends longitudinally through the housing, each bolt is uniformly actuated in the vertical direction, concomitantly to carry the floating section therewith. Each cap member 91 and 92 is provided with a cup shaped end cap 95 for receiving the respective bolt when actuated upwardly.

Extending forwardly of the spiral gear housing 23 is a spindle 96, which is integral with the worm 94. The spindle end is adapted to receive a crank (not shown) for manually actuating the same, the amount of turning movement being indicated by a dial 96' for control purposes. In this manner, merely by turning the worm in one direction or the other as desired, the floating section, which is constantly in balanced relation, thereby to militate against binding or bearing wear, may be actuated rapidly in one direction or the other for roll interchange purposes, or for minutely and accurately adjusting the upper roll 10 vertically with respect to the lower roll 11.

For the purpose of maintaining a driving relation at all times between the roll shafts 12 and 13 even though the upper driven shaft is vertically and longitudinally adjusted relative to the lower driving shaft, there is provided a pair of intermediate spur gears 98 and 99. A shaft 100, which carries the upper spur gear 98, is journaled in bearing portions 101 which are connected by links 102 to bearing sections 103. The bearing sections 103 are mounted on sleeves 104 which are integral with the cap members 70 and 76 respectively. The link is of a length permanently to maintain full meshing relationship between the spur gear 98 and the gear 68 on the upper shaft 12. Gear 99 is maintained in full meshing relation with the gear 68 and in turn meshes with the gear 38 keyed to the lower shaft 13 by means of a link 105. The link 105 connects the bearing portions 101 with the bearing sections 106 which provides mounting for a shaft 107 for the gear 99, and sleeves 108. The sleeves 108 of the link 105 rotatably engage sleeves 109 which are integral with and extend laterally of the cap members 40 and 43.

From the description of a preferred embodiment of the invention, it is manifest that I have produced a continuously operating tube mill in which each pair of forming roll mounting shafts is journaled in an improved roll housing. In the

housing, one roll shaft, which is mounted in a floating section, is adapted to be driven by the other through gearing connected by linkage which maintains the gears in full meshing relation even though one shaft is adjusted vertically and longitudinally relative to the other. Longitudinal shifting movement of the one shaft with relation to the other is simply and readily effected merely by the actuation of a single screw member, which effects the desired longitudinal movement, bodily along its own axis, of the entire shaft structure within the floating section. Vertical adjustment is as readily obtained and controlled by means effecting the adjustment of the guided floating section, which includes a single driving member for actuating the floating section mounting means uniformly in one vertical direction or the other without the danger of misalignment or such unbalancing as would result in the binding of the shaft mounting bearings.

It is readily apparent that considerable saving in time and improvement in accuracy results from means enabling the adjustment of one roll shaft vertically or longitudinally relative to the other in response to the actuation of a single member. Thus there is eliminated the arduous and time consuming task of balancing the adjusted shaft or its mounting means and the danger of damage to the equipment as a result of misalignment or subsequent shifting of parts.

It is to be understood that numerous changes in the details of construction, arrangement and operation of part may be effected without departing from the spirit of the invention, especially as defined in the following claim.

I claim:

In a tubing machine, tube forming mechanism including a pair of cooperating forming rolls, parallel driving and driven shafts for said rolls, means for supporting said driving and driven shafts including sleeve means rotatably carrying said driven shaft, roller bearings for said driven shaft carried by said sleeve means, at least one of which bearings is fixed to the driven shaft to prevent relative axial movement between the two, and means for axially adjusting said driven shaft slightly relative to said supporting means, said adjusting means including a flanged slid able sleeve member forming part of said sleeve means and engaging said fixed roller bearing in a manner to effect axial movement thereof in either direction, a non-rotatable screw secured to a fixed portion of said supporting means and extending parallel to the driven shaft and extending through the flange of said sleeve member and a nut on said screw on each side of the flange of said sleeve member so that by loosening one nut and tightening the other axial adjustment of the sleeve member is effected in one direction or the other.
